UNITED STATES PATENT OFFICE.

JOHN JAMES WILSON, OF COLUMBIA, TENNESSEE.

BOX-STRAPPING DEVICE.

1,297,283.

Specification of Letters Patent. Patented Mar. 11, 1919.

Application filed July 3, 1918. Serial No. 243,218.

To all whom it may concern:

Be it known that I, JOHN J. WILSON, a citizen of the United States, residing at Columbia, in the county of Maury and State of Tennessee, have invented certain new and useful Improvements in Box-Strapping Devices; and I do hereby declare the following to be a full, clear, and exact description of the invention, such as will enable others skilled in the art to which it appertains to make and use the same.

This invention relates to tensioning wire, cord, or the like, and particularly relates to a box banding tool. It is one of the objects of the present invention to provide a simple, substantially constructed, durable, easily operable and practicable device for facilitating the banding of boxes or the like by drawing about the same a band of wire. It is one of the objects of the present invention to provide a device of this type in which the parts are simple and inexpensive, and which may be rapidly and accurately adjusted and operated in the banding of a box. Another object of the invention is to provide a simple means for opening and closing a set of gripping jaws; to provide means for holding the relatively movable elements of the device temporarily in any given position; and further to provide means for preventing the clogging or jamming of the device because of the banding element or wire becoming caught between the elements of the tool in such positions that would render the tool clogged.

With the above and other objects in view as will be rendered manifest to those skilled in the art, the invention consists of the construction, the combination, and in details and arrangements of the parts as more particularly hereinafter set forth relative to the embodiment of the invention illustrated in the accompanying drawing, in which—

Figure 1 is a perspective view of the device in application, and

Fig. 2 is a cross section through the beam just above the top of the slide.

The tool comprises a main jack member or beam 2 at the upper end of which is provided a suitable purchase member 3, and at its lower end is formed to normally engage a rest or support or portion of a box, for instance, to be bound and grapple a piece of wire W, which is provided with an eye resting against the bifurcated point 4 of the beam 2, while the stretch or band of

wire is thenice led around the box to be bound and forwardly and upwardly through the eye and into a position between a pair of jaws or gripping means on the beam. In this case the gripping means comprises a pair of toothed jaws 5—5 set on pivots 6—6 the faces of the jaws being opposed to each other so that when moved downwardly on their pivots they will embrace the interposed stretch of wire. To secure the automatic closing of the jaws on the wire they are each provided with an outwardly extending lever arm 7 to the ends of which is attached a link or rod 8, the upper end of each rod being connected at 9 to a handle or lever 10 of suitable construction which is pivoted at 11 on a part of or on the beam 2. The fulcrum or pivot 11 of the operating lever 10 is shown on one side of the beam across which the lever extends transversely, the pivoting point 9 of the connecting rod being disposed between the pivot 11 of the lever and its swinging end. The gripping means or jaws have their pivots 6 mounted on a side face of a slide 12 shown as encompassing the body of the beam 2 and in operation when the lever 10 is pulled away from the grapple point 4, the jaws 5—5 are swung toward each other to embrace the wire and then further movement of the lever 10 causes the jaws and slide 12 to move bodily up the beam thus placing the wire under the desired tension.

To secure the slide 12 at any desired position along the beam 2, a suitable means may be employed here illustrated as comprising a brake spring 13 interposed between one element of the slide 12 and the adjacent body of the beam 2.

In order to prevent the wire which is to be tensioned from jamming or clogging by becoming caught between the faces of the jaws 5—5 and the adjacent side of the slide 12, the latter is provided with a transversely projecting lug 14 in the meeting plane of the jaws 5—5, this preventing the wire from being pushed so close to the face or side of the slide 12 that it could pass between the slide and the jaws.

What is claimed is:

1. A box banding tool comprising a beam having one end notched and adapted to bear upon a box element and straddle a wire having an eye in its end; a lever pivoted on the beam; a slide mounted on the beam between the lever and the beam point; grip-

- ping jaws on the slide; and link connections between the jaws and the lever whereby the jaws are opened and closed by the lever to draw a part of the wire through said eye.
- 5 2. A box banding tool comprising a beam having one end adapted to bear upon a box element and straddle a wire having an eye in its straddled end; a lever pivoted on the beam; a slide mounted on the beam between the lever and the beam point; gripping jaws on the slide to bite upon a part of the looped wire passed through the eye, and connections between the jaws and the lever whereby the jaws are opened and closed 10 by the lever, the latter first closing the jaws and then bodily shifting the slide and jaws when moving away from the notched end of the beam and pulling the wire in the same direction that the lever moves.
- 15 3. A box banding tool comprising a beam having one end provided with a V-notch and adapted to bear upon a box element and straddle a wire laid on said element; a lever pivoted on the beam; a slide mounted on the beam between the lever and the beam point; gripping jaws on the slide, connections between the jaws and the lever whereby the jaws are opened and closed by the lever, and brake means for holding the slide 20 in different positions along the beam.
- 25 4. A box banding tool comprising a beam having one end adapted to bear upon a box element and straddle a wire; a lever pivoted on the beam; a slide mounted on the beam between the lever and the beam point; gripping jaws on the slide, connections between the jaws and the lever whereby the jaws are opened and closed by the lever, and means for frictionally holding the slide 30 in different positions along the beam.
- 35 5. A box banding tool comprising a beam having one end bifurcated and adapted to bear upon a box element and straddle a wire; a lever pivoted on the beam; a slide mounted on the beam between the lever and the beam point; gripping jaws on the slide, connections between the jaws and the lever whereby the jaws are opened and closed by the lever, and means for holding the slide 40 in different positions along the beam, said holding means comprising a spring brake reacting between the slide and beam.
- 45 6. A box banding tool comprising a beam having one end bifurcated and adapted to bear upon a box element and straddle a wire; a lever pivoted on the beam; a slide mounted on the beam between the lever and the beam point; gripping jaws on the slide; and connections between the jaws and the lever whereby the jaws are opened and 50 closed by the lever, the slide having means for preventing the wire from becoming disposed between the sides of the jaws and the adjacent face of the slide.
- 55 In testimony whereof I affix my signature.
JOHN JAMES WILSON.
